UNITED STATES PATENT OFFICE.

SAMUEL C. PERRY, OF LONDON, KENTUCKY.

RAILWAY-SWITCH.

1,077,427.

Specification of Letters Patent.

Patented Nov. 4, 1913.

Application filed March 16, 1912. Serial No. 684,274.

To all whom it may concern:

Be it known that I, SAMUEL C. PERRY, a citizen of the United States, residing at London, in the county of Laurel and State of Kentucky, have invented a new and useful Railway-Switch; and I do hereby declare the following to be a full, clear, and exact description of the invention, such as will enable others skilled in the art to which it appertains to make and use the same.

This invention relates to a new and useful railway switch.

It is the primary object of this invention to improve the structure of the switch mechanism shown in the drawings and set forth in the application, filed Oct. 18, 1911, Serial No. 655,444, and to provide an improved switch throwing mechanism adapted to be operated by a member on a moving car.

Another object of the invention is the provision of a switch, which when accidentally or otherwise left open, will automatically close upon the approach of a moving train.

A further object of the invention is to provide a lock for the switch adapted to be actuated by a member on a moving car or train, so as to release or unlock the switch, before the switch is thrown. This switch is provided with the usual signal, which indicates whether the switch is open or closed.

If the switch is accidentally or otherwise left open, and the moving train is approaching the switch from the front on the main line, the switch mechanism is first unlocked automatically by the member on the moving train, after which the switch is automatically closed by the same member on the train. This operation is carried out in cases when the train is to continue straight ahead.

However, if the train is approaching the switch on the main rails in the rear of the switch points, the switch is first automatically unlocked by the same member, after which the switch points are thrown automatically by the flanges of the car wheels.

The invention comprises further features and combination of parts, as hereinafter set forth, shown in the drawings and claimed.

In the drawings:—Figure 1 is a plan view of the improved railway switch embodying the features of the invention. Fig. 2 is a similar view, showing the switch points thrown in different positions. Fig. 3 is an enlarged detail view of a portion of the switch mechanism, showing the lock mechanism for locking the switch points. Fig. 4 is a sectional view on line 4—4 of Fig. 3.

Fig. 5 is a sectional view on line 5—5 of Fig. 3. Fig. 6 is a detail view of the locking bolt. Fig. 7 is a perspective view of a pivoted bar to be actuated by the wheel member on the moving train to unlock the switch, when the train approaches the switch in the rear of the switch point. Fig. 8 is a detail view in end elevation of the structure shown in Fig. 7, looking in the direction of the arrow *k*. Fig. 9 is a sectional view upon line 9—9 of Fig. 1. Fig. 10 is a detail perspective view of the structure shown in Fig. 9. Fig. 11 is a view in perspective of the mechanism to be actuated by a member on a moving train for unlocking the switch, that is, when a train is to pass from the branch line to the main line and vice versa. Fig. 12 is a view in elevation of the mechanism in Fig. 11. Fig. 13 is a view in perspective of the device adapted to be actuated by a member on a moving train, for throwing the switch after being unlocked, when a train is to pass from the branch line to the main line, and vice versa. Fig. 14 is a sectional view on line 14—14 of Fig. 13. Fig. 15 is a plan view on an enlarged scale to be actuated by a member on a moving train, for unlocking the switch, when the switch points are accidentally or otherwise left open, and when the train is to continue straight ahead on the main line. Fig. 16 is a sectional view on line 16—16 of Fig. 15. Fig. 17 is a view in perspective of an oscillatory forked member having two flanged wheels, one of which is to be thrown in engagement with the rails, for actuating the mechanism in Fig. 15, while the other is brought in play to operate the devices shown in Figs. 11, 12, 13, and 14.

Referring to the drawings 1 and 2 designate the rails of the main line, on one side of the switch points, while 3 and 4 denote the main rails on the other side of the switch points, whereas 5 and 6 designate the rails of the siding or branch line. The switch points 7 and 8 are pivoted at 9 and 10. Connecting the free ends of the switch points by the straps 12 is a bar 13, in which a slot 14 is formed. Pivoted in the slot 14 is a latch member 15, between which and an angular lug 16 of the bar 13, a spring 17 is interposed, the action of which normally holds the latch member 15 pressed upwardly, so that the lug 18 of the latch member will engage on either side of the locking bolt 19, which is mounted in guides 20 on the ties 21. The locking bolt 19 is provided with diag-

nally opposite recesses 22 and 22^a having beveled portions 23, so that when the lug 18 is in registration with either one of the recesses, the bar 13 may be reciprocated transversely of the rails, thus throwing the switch points to an open or closed position. Pivoted at 25 is an angular lever 26, one arm of which has one end of a rod 27 connected to it, while the other end of the rod 27 is pivoted at 28 to the three armed rocking member 29, which is pivoted at 30. This three armed rocking member has a slot and pin connection 31 with the bar 13, so that when the member 29 is rocked, the bar 13 will be thrown one way or the other, to in turn throw the switch points. Adapted to reciprocate transversely of the rails, one upon each side of the switch points are the bars 33 and 34. The bar 33 is provided with a slot and pin connection 35 with the other arm of the angle lever 26. The bar 34 is also provided with a slot and pin connection 36 to one arm of the angle lever 37, which is pivoted at 38. The other arm of the lever 37 has one end of a rod 39 connected to it, the other end of which rod 39 is pivoted at 40 to the three armed rocking member 29. Pivoted at 41 is a lever 42, to one end of which a rod 43 is connected. When this rod 43 is reciprocated in the direction of the switch point, the lever 42 is oscillated. The lever 42 is provided with a slot and pin connection 44 with the locking bolt 19, so that when the lever 42 is manipulated the bolt 19 will in turn be reciprocated.

The bolt 19 has secured to it by the pins 19^b and 19^c, a spring 19^a, which arches upwardly substantially at its central portion, between the guides 20, in order to hold the bolt 19 in one position or the other. The pins 19^b and 19^c not only secure the spring 19^a in position, but also constitute means for limiting the bolt 19 in its movement.

Pivoted to the rails 1, 2, 5 and 6 as at 46 are the depressible bars 47, 48, 49, and 50. The pivots 46 of these depressible bars are in the form of slot and pin connections, as shown at 51 in Figs. 11 and 12. Mounted in bearings 52, and in the bearings of the said rails 1, 2, 5 and 6 are the rocking rods 53, 54, 55, and 56, which are provided with cranks 57, 58, 59, and 60. These rocking rods are also provided with the cranks 61, 62, 63 and 64. The depressible bars 47, 48, 49 and 50, which are spring tensioned as shown at 66 in Figs. 11 and 12, coöperate with the cranks 61, 62, 63 and 64, so as to rock the said rocking rods. The end 68 of the rod 43 connects to the crank 59 of the rocking rod 55.

Pivoted at 69, 70, 71 and 72 are the switch actuating bars 73, 74, 75, and 76, which are held adjacent the rails by the springs 77, the tension of which is regulated by the nuts 78. Each of the switch actuating bars is

provided with a recess 79 to receive the transversely reciprocating bars 33 and 34, with the lugs 80 of which the switch actuating bars coöperate, in order to move the bars 33 and 34 one way or the other.

If the switch is accidentally or otherwise left open, as shown in Fig. 2, and a train is approaching the switch points in the direction of the arrow *a*, the wheel 81, which is normally in engagement with the rail 2 in this case actuates the switch unlocking bar 82, which is pivoted at 83, by the flange 84 of the wheel coming in contact therewith. This operation is performed when the train is to continue straight ahead on the main line. It will be observed that this switch unlocking bar 82 is positioned, so that the flanges of the car wheel will not contact therewith ordinarily. The free end of this bar 82 is guided in the guide 85. When the bar 82 is actuated, it in turn actuates the bell crank lever 86, by virtue of its connection 87. The bar 82 is pivoted upon a guide rail 88, as shown clearly in Figs. 15 and 16.

The bell crank lever 86 has its arm 89 connected to the rod 90, which in turn is pivoted at 91 to the lever 42. Thus it will be seen that as the lever 86 is oscillated the lever 42 will in turn be rocked, which will actuate the bolt 19, so that the bar 13 may be reciprocated, in order to restore the switch points 7 and 8 to the positions shown in Fig. 1, whereby a train may continue straight ahead upon the main line. After the bar 13 has been unlocked in this manner, the flange 84 of the wheel 81 actuates the supplemental switch actuating bar 95, which is pivoted at 96 upon a guide rail 97. The free end of the bar 95 is guided in the guides 98. The bar 95 is pivoted, by virtue of the lug 99 to the transversely reciprocating bar 33, as shown at 100. When the bar 95 is thrown away from the rail 2 by the flange 84 of the wheel 81, the reciprocating bar 33 is actuated in the direction of the arrow *b*, and by reason of the slot and pin connection 35 with the lever 26, the three armed member 29 is oscillated, which in turn will actuate the bar 13, thus restoring the switch point to the positions shown in Fig. 1.

However, if a train is approaching the switch points on the main line in the direction of the arrow *c*, while the points are in the positions shown in Fig. 2, the switch unlocking bar 102 is actuated by the flange 84 of the wheel 81, as shown clearly in Figs. 7 and 8. This bar 102 is pivoted at 103, and is arched upwardly between its ends, as shown in Fig. 7, with its free end guided in the guides 104. When the bar 102 is actuated, the bell crank lever 105 which is pivoted at 106 is actuated, by virtue of the rod connection 107. This rod 107 pushes against the bell crank lever 105 and oscillates it in the direction of the arrow *e*. The arm 108

of the lever 105 is connected at 109 to the rod 43, and when the bell crank lever 105 is oscillated in the direction of the arrow *e*, the rod 43 is moved, which in turn will 5 swing the lever 42 upon its pivot 41, thus throwing the bolt 19, in order that the switch points 7 and 8 may be thrown by the flanges of the car wheels. As the train leaves the switch, still traveling in the direction of the arrow *e*, the switch is again 10 locked, by virtue of the wheel 110 of the forked member 111 (which also carries the wheel 81) coming in contact with the depressible bar 48. When the bar 48 is depressed, the rocking rod 54 is actuated, because of the crank 62 being actuated. If 15 desired the wheel 110 need not be thrown in a position to actuate the depressible bar 48. Referring to Fig. 1, it will be seen that 20 when a train is moving in the direction of the arrow *d*, the flange of the wheel 110 depresses the bar 47, which in turn actuates the rocking rod 53, by virtue of the crank 61. As the rod 53 is rocked, the crank 57 25 contacts with the shoulder 113 on the rod 90, moving the rod 90 in the direction of the switch points, thus oscillating the lever 42, which in turn throws the bolt 19, thus releasing or unlocking the bar 13. This operation 30 is performed when the train is to pass on the branch line. After the bolt 19 is thrown in this manner, the flange of the wheel 110 throws the switch actuating bar 74, against the action of its spring, thereby moving the 35 bar 33 transversely of the rail. When the bar 33 is thus actuated, the three armed member 29 is oscillated on its pivot, which in turn throws the bar 13 and the switch points 7 and 8 with it to the positions shown 40 in Fig. 2, thus permitting the train to take the branch line. As the train leaves the switch mechanism, the flange of the wheel 110 actuates the depressible bar 50, which in turn rocks the rod 56, by virtue of the crank 45 64. When the rod 56 is actuated the crank 60 contacts with the shoulder 116 of the rod 43, thus unlocking the switch points. As the train continues on the branch line, the flange of the wheel 110 actuates the bar 75, 50 which in turn moves the bar 34. When the bar 34 is transversely moved, the bell crank lever 37 is oscillated, which in turn will throw the switch points, by means of the rod 39, the three armed member 29, and the 55 bar 13.

When a train is approaching the switch on the branch line in the direction of the arrow *h*, the switch is unlocked by depressing the bar 49, so as to rock the rod 55, 60 which in turn will push the rod 43 in the direction of the switch points 7 and 8. After the switch has been unlocked as the train is moving in this direction, the switch points are thrown by actuating the bar 76. 65 As the train leaves the switch passing in

the same direction of the arrow *h*, the switch is again unlocked and thrown or restored to its former position by first actuating the depressible bar 48, and then the bar 73.

To move the bar 13 by hand, a rod 70^a mounted in guides 71^a is moved longitudinally, so that the cam member 72^a thereon will actuate the latch member 15, so as to throw the lug 18 from the path of the locking bolt 19. This rod 70^a may be locked to a lever of the signal post 75^a so that the switch cannot be opened, until the padlock 76^a is unlocked. However, when the padlock is unlocked the rod 70^a may be reciprocated thus actuating the latch member 15. 75 When the bar 13 is moved transversely, it in turn actuates the signal (not shown) by virtue of the rack 75^c and pinion 75^b with the signal post 75^a. The signal post 75^a is provided with a loose sleeve having 80 an arm 76^b, which sleeve is located between the fixed collars 75^e. Pivoted to the arm 76^b is a link 76^d, which terminates in an eye. The rod 70^a turns upwardly through an opening 70^e, and to its end a link 76^e is 85 pivoted. This link 76^e terminates in an eye 76^c, which and the eye of the link 76^d receive the padlock 76^a.

From the foregoing it will be noted there has been devised a novel, simple, efficient 95 switch mechanism adapted to be automatically operated by a member on the moving car, and one which has been found to be practical.

The invention having been set forth, what 100 is claimed as new and useful is:—

1. In a switch, a pair of switch points, a transverse member secured to the switch points and provided with an elongated slot, a spring latch member pivoted in the slot, 105 and a shifting locking bolt for coöperating with the latch member for locking the switch points open or closed.

2. In a switch, a pair of switch points, a transverse member secured to the switch points and provided with an elongated slot, a spring latch member pivoted in the slot, 110 and a shifting locking bolt for coöperating with the latch member for locking the switch points open or closed, means actuated by 115 a member on the car for shifting the locking bolt to permit the latch member to pass the same when the switch points are moved, and means adapted to be actuated by a member on the car for moving the switch points. 120

3. In a switch, a pair of switch points, a transverse member secured to the switch points and provided with an elongated slot, a spring latch member pivoted in the slot, 125 and a shifting locking bolt for coöperating with the latch member for locking the switch points open or closed, and means for manually moving the transverse member for moving the switch points, said means including manually manipulated means for throwing 130

the latch member from coöperation with the shifting locking bolt prior to moving the transverse member.

4. In a switch, a pair of switch points having a transverse member provided with a spring retained latch member, the latch member having a lug, a locking bolt having diagonally opposite recesses provided with beveled portions, the locking bolt having solid walls opposite the recesses against which the lug engages, for locking the transverse member and the switch points open or closed, means adapted to be actuated by a member on the car for shifting the locking bolt, to bring one or the other of the recesses in registration with the lug of the latch, and means adapted to be actuated by a member on the car for throwing the transverse member so as to cause the lug of the latch member to enter one or the other of the recesses, so as to unlock the transverse member and the switch points.

5. In a switch, a pair of switch points including a locking mechanism therefor, a guide rail, a switch unlocking bar pivoted on the guide rail and adapted to be oscillated by a member on a moving train, a guide for the free end of the switch unlocking bar, and connections between the switch unlocking bar and the locking mechanism.

6. In a switch, a pair of switch points including a locking mechanism therefor, a guide rail a switch unlocking bar pivoted on the guide rail and adapted to be oscillated by a member on a moving train, a guide for the free end of the switch unlocking bar, and connections between the switch unlocking bar and the locking mechanism, a second guide rail, a switch point actuating bar pivoted on the second guide rail in a reverse position to the switch unlocking bar, a guide for the switch point actuating bar, and connections between the switch actuating bar and the switch points.

7. In a switch, a pair of main rails, a pair of branch rails having a pair of switch points including a locking mechanism therefor, a bar movable transversely of and guided in the main rails and provided with lugs at either end, a switch actuating spring tensioned bar pivoted to one of the main rails to coöperate with one of the lugs of the transversely movable bar for throwing the same, a rocking crank rod journaled in bearings of the main track, and a depressible bar to actuate the crank rocking rod, connections between the crank rocking rod and the locking mechanism for unlocking the switch points, and connections between the transversely movable bar and the switch points for throwing the points when the transversely movable bar is actuated.

8. In a switch, a pair of switch points, a transverse member secured to the switch points and provided with an elongated slot, a spring latch member pivoted in the slot, and a shifting locking bolt for coöperating with the latch member for locking the switch points open or closed, a guide rail, a switch unlocking bar pivoted on the guide rail and adapted to be operated by a member on a moving car, a guide for the free end of the switch unlocking bar, and connections between the switch unlocking bar and the shifting locking bolt for manipulating the bolt.

9. In a switch, a pair of switch points, a transverse member secured to the switch points and provided with an elongated slot, a spring latch member pivoted in the slot, and a shifting locking bolt for coöperating with the latch member for locking the switch points open or closed, a guide rail, a switch unlocking bar pivoted on the guide rail and adapted to be operated by a member on a moving car, a guide for the free end of the switch unlocking bar, and connections between the switch unlocking bar and the shifting locking bolt for manipulating the bolt, a second guide rail, a switch point actuating bar pivoted on the second guide rail in a reverse position to the switch unlocking bar, a guide for the switch point actuating bar, and connections between the switch point actuating bar and the switch points for throwing the same, the switch unlocking bar and the switch point actuating bar adapted to be actuated by a member on a car.

10. In a switch, a pair of switch points, a transverse member secured to the switch points and provided with an elongated slot, a spring latch member pivoted in the slot, and a shifting locking bolt for coöperating with the latch member for locking the switch points open or closed, and means for manually moving the transverse member for moving the switch points, said means including manually manipulated means for throwing the latch member from coöperation with the shifting locking bolt prior to moving the transverse member, means in addition to the manually operated means adapted to be operated by a member on a car for shifting the locking bolt, to permit the latch member to pass the same when the switch points are moved, and means in addition to said means included in the manually manipulated means adapted to be actuated by a member on a car for throwing the switch point.

In testimony whereof I have signed my name to this specification in the presence of two subscribing witnesses.
